Primary Examiner — Jeffrey D Asch(74) *Attorney, Agent, or Firm* — Robert C. Montgomery; Montgomery Patent & Design**CLAIM**

The ornamental design for a keyboard with a touchpad, as shown and described.

DESCRIPTION

FIG. 1 is a perspective view of a keyboard with a touchpad, showing my new design;

FIG. 2 is a front view thereof;

FIG. 3 is a rear view thereof;

FIG. 4 is a left hand view thereof;

FIG. 5 is a right hand view thereof;

FIG. 6 is a top view thereof; and,

FIG. 7 is a bottom view thereof.

The broken lines shown in the figures that are immediately adjacent to the shaded areas and define regions that are consistently unshaded, represent the bounds of the claim, while all other broken lines are directed to environment and are for illustrative purposes only; the broken lines form no part of the claimed design.
